UNITED STATES PATENT OFFICE.

GUSTAVUS A. MONTGOMERY, OF OILFIELDS, CALIFORNIA, ASSIGNOR OF ONE-THIRD TO
RUDOLPH H. STICHEL, OF OILFIELDS, CALIFORNIA.

ROPE-SOCKET.

1,153,812.

Specification of Letters Patent. Patented Sept. 14, 1915.

Application filed August 26, 1914. Serial No. 858,626.

To all whom it may concern:—

Be it known that I, GUSTAVUS A. MONTGOMERY, a citizen of Finland, subject of the Emperor of Russia, and a resident of Oil-fields, in the county of Fresno and State of California, have invented a new and Improved Rope-Socket, of which the following is a full, clear, and exact description.

My invention relates to sockets for well-drilling cables or ropes.

An object thereof is to provide a socket which can be used as a swivel or solid rope socket, which can be easily and quickly changed from one to the other, which is simple and strong in construction, which has its movable parts protected from abrasive material present in wells and which movable parts within the socket are perfectly lubricated. A drilling tool is generally provided with a single cable, and it becomes necessary to cut the cable every time there is a change from a solid to a swivel socket or vice versa. This requires a great deal of time and care. Very often the change is only for a short period of time and the connection between the socket and the rope is not made very carefully, the result being the disconnection of the rope from the socket, causing a great deal of delay, as the drilling tool, remaining in the well must be extracted, and this generally takes a great deal of time. To obviate the above defects, I have provided a socket which can be quickly changed from a solid rope socket to a swivel rope socket, or vice versa, not only without any necessity of cutting the rope but even without interfering in any way with the connection of the rope with the socket.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is a horizontal section on line 1—1, Fig. 2; Fig. 3 is a vertical, axial section through the socket; Fig. 4 is an elevation, partly in section, of a slightly modified structure of the socket; and Fig. 4 is an elevation of a rope socket with a 55 spacer, partly in section.

Referring to the drawings, more particularly Figs. 1 and 2, 5 is the shell of the socket the cylindrical surface of which is stepped, decreasing in diameter from the base to the top. The shell 5 is provided with an axial bore formed of three cylindrical sections 6, 7 and 8. Section 6 is the longest, has the largest diameter, and is located at the lower end of the bore. Section 8 has a slightly smaller diameter and is located adjacent the upper end of the shell. Section 7 is the narrowest and the shortest and connects the two sections 6 and 8 of the bore, whereby two shoulders 9 and 10 are formed within the shell 5. The shoulder 9 is formed by the bore 6; and the shoulder 10, by the bore 8. Fitting tightly into the bore 6 is a steel-hardened washer 11 which abuts with one face thereof against the shoulder 9. The other face of the washer is concave, forming a seat for the upper end of the rope head or core 12.

The head 12 has a central funnel-shaped bore which engages the end of the cable 13 and which end is babbitted to the head. Before the babbitt is cold a spring-guide washer 14 is inserted into the lower end of the bore of the head 12, purposely made cylindrical for said washer 14. The cooling babbitt which seals the cable end of the head also locks the spring-guide washer 14 to the head. The head 12 is maintained against the washer 11 by a cushion spring 15, one end of which abuts against the washer 14 and the other end rests on the shoulder of a center piece 16 mounted within a recess 17 of an adjustable plug 18 threaded into the bore 6 below the head 12. The adjustable plug is provided with an angular recess 19 to be engaged by a wrench from the end of the bore 6, whereby the same can be moved to or from the head 12. The adjustable plug 18 can be locked in different positions by a set screw 20 operable from the outside of the shell. This permits variation in compression of the cushion spring 15. By moving the plug 18 against the head 12, the center piece 16 will abut against the spring-guide washer 14 and thereby prevent the rotation of the head within the bore 6. The adjustable plug 18 is moved against the head when the socket is to be converted into a solid socket for a long period of time. When the swivel socket is to be converted into a solid socket for a 310

short period of time, the cable head 12 can be prevented from rotation by a set screw 21 operable from the outside of the shell without moving the adjustable plug 18.

5 The contact of the washer 14 with the center piece 16 is shown in Fig. 3.

Mounted to move freely within the bore section 8 is a guide sleeve 22 which is babbitted to the cable 13. The lower end of the 10 sleeve 22 has the bore for the cable slightly enlarged, so that the bottom of the enlarged portion of the bore will form a seat for the leather washer 23, which will make a tight joint between the bore for the cable and the 15 enlarged portion of said bore. A steel washer 24 is maintained against the leather washer by an equalizing spring 25 mounted on the cable 13 between the shoulder 10 and the said steel washer.

20 The upper portion of the sleeve 22 is exteriorly reduced in diameter, and the upper end thereof fits snugly into the central bore of a cap 26 threaded into the upper end of the bore section 8, the cap 26 being locked 25 to the shell 5 by a set screw 27 or any other suitable means. The lower part of the bore in the cap 26 is enlarged to receive a spongy washer 28 resting against the bottom formed by the enlargement of the bore. A steel 30 washer 29 is positioned between the spongy washer 28 and packing rings 30. This arrangement of the packing rings, spongy washer, and the metallic washer forms a stuffing box for the adjusting sleeve 22 with 35 in the cap 26. The packing rings are self-adjustable under the action of an adjusting spring 31 positioned on the reduced portion of the sleeve 22. A washer is preferably provided between the end of the spring and 40 the packing ring to reduce friction during the use of the contrivance as a swivel socket. This arrangement prevents the abrasive material present in the well from working its way between the adjusting sleeve and the 45 cap 26. Although the sleeve 22 is babbitted to the cable 13, a passage may be left where the sand may work its way between the sleeve and the cable, and to prevent this a leather washer 32 is mounted on the cable 50 over the cap 26, and the end of the guide sleeve 22 is made to slightly project from the cap so as to enter the leather washer which is maintained against said cap and end of sleeve by a coil spring 33, the upper end of 55 which abuts against a collar 34 formed on the cable.

The guide sleeve 22 and the cable head 12 are made to work in a lubricant, which is introduced into the bore sections 6 and 8 60 through the bore section 7 by providing a threaded aperture 35 leading from the side of the shell into said bore section and normally closed by a plug 36. By removing the plug a grease cup can be inserted and the 65 lubricant forced through the bore section 7

into the lower and upper bore sections 6 and 8 respectively. The threaded aperture 35 is also used for severing the cable 13 when necessary to remove the cable head 12 and the guide sleeve 22. The guide sleeve 22 and the cable head 12 are provided on their lateral surfaces with helical grooves 37 to feed the grease along the surface of the bore sections so as to obtain a better lubrication. The shell 5 at the lower end of its axial bore 75 is provided with the customary bevel thread 38 whereby it can be secured to the drilling tools or any other tools that may be necessary in the process of drilling. The shell has a part of its lateral surface shaped angularly, as shown at 39, whereby the same can be handled with a suitable wrench.

The connection of the cap 26 with the shell 5, as shown in Fig. 2, is only used when the diameter of the well does not permit 85 countersinking of the cap 26', as shown in Fig. 3. This is due to the fact that in relatively small drill holes the upper end of the shell 5 must be reduced sufficiently to facilitate the extracting of tools that may be made 90 necessary by a rupture of the cable.

In Fig. 4 a further modification of the shell is shown, by making the lower threaded end of the bore 38' cylindrical, for the reason that the cone-shaped end will greatly 95 reduce the diameter of the bore section 6, which is not desirable; and to obviate this, the bore is made cylindrical and an extension 40 is inserted between the cable socket and the tools to be connected thereto. It is 100 understood that the extension 40 is for use only in small sockets for small sized drill holes.

To fasten the socket to the cable, care must be taken to put all parts on the cable in the 105 order shown in the drawings, from the top to the bottom; then the end of the cable 13 is expanded and forced into the funnel part of the head 12, molten babbitt being poured on top of the expanded end into the head. Before the babbitt cools, the washer 14 is 110 inserted into position. The socket is then suspended on the cable 13 so that the head will seat itself against the washer 11. The bore of this washer 11 is preferably made a 115 little smaller than the diameter of the bore section 7, so that the washer can be easily removed by a rod fitting snugly into the bore section 7. The adjustable plug 18 can then be screwed into position and the compression of the cushion spring 15 thereby adjusted and the plug locked to the shell by the set screw 20. This will permit the head 12 to turn within the shell. The guide sleeve 22 is then moved on the cable to enter into the bore section 8 with all the parts associated therewith, the cap 26 being screwed down and locked by the set screw 27. Molten babbitt is then poured between the cable 120 and the sleeve, the leather washer at the bot- 125 130

tom forming a tight bottom for the sleeve bore. Preferably grooves 41 are provided within the bore of the sleeve so as to give a better grip to the babbitt. The leather washer 32 is then forced against the top of the cap and the end of the sleeve, and the conical spring 33 is then tied to the cable so as to maintain said washer against the cap of the sleeve as stated. If it is desired now to change the swivel socket to a solid socket for a short period of time, the set screw 21 is used, whereby the head 12 is locked to the shell; but when the contrivance is to be used for a solid socket for a long period of time, the adjustable plug 18 is moved against the head 12, as described, and in addition the set screw 21 may also be used.

It will be noticed that all the moving parts of my socket are completely cushioned by springs, preventing hammering and, consequently, wear. Further, all the moving parts are submerged in a lubricant and abrasive material is prevented from entering and injuring the moving parts. It simplifies and reduces the cost of operation, in that one socket answers the purpose of two. Further, a great saving in time is secured when a change from a swivel to a solid socket, or vice versa, is necessary.

From the foregoing description, taken in connection with the accompanying drawings, the advantage of the construction and operation of the device shown will be readily understood by those skilled in the art to which the invention pertains; and while I have described the principle of operation, together with the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. A drilling cable socket comprising a shell, a cable head mounted to rotate and slide in the shell, resilient means normally resisting the relative sliding movement of said head and shell, and means for varying the resiliency of the spring adapted to lock said head to the shell.

2. A drilling cable socket comprising a shell, a cable head connecting the cable to the shell, said head being mounted to rotate and slide in the shell, an adjustable plug inclosing the head in the shell, a resilient member positioned between the head and the plug whereby the relative displacement between the shell and the head is controlled, and set screws for locking independently said head to the shell and said plug thereto

substantially as and for the purpose set forth.

3. A drilling cable socket comprising a shell, a cable head adapted to connect the cable to the shell, said head being mounted to rotate and slide in the shell, a guide sleeve carried by the cable and mounted to slide and rotate in said shell, an adjustable plug sealing said head in the shell and adapted to lock the same to the shell, whereby the relative movement between the shell and head is prevented, a stuffing box for said sleeve, and cushioning means associated with said head and sleeve for resisting a relative movement between the cable and the shell.

4. A drilling cable socket comprising a shell, a cable head mounted to rotate and slide in the shell, said head having a convex end, the shell having a concave shoulder, a resilient member maintaining the convex end of the head against the concave shoulder of the shell, and means for varying the tension of said resilient member.

5. A drilling cable socket comprising a shell having a through bore enlarged at both ends, a cable head mounted to rotate and slide in the lower enlarged portion of the bore, a plug closing the enlarged end of the bore engaged by the head, a resilient member between the plug and the head, a guide sleeve carried by the cable engaging the enlarged portion of the bore at the upper end, a cap closing the bore and engaging the sleeve, and balancing resilient means within the enlarged bore portion and associated with the sleeve, substantially as and for the purpose set forth.

6. A drilling cable socket comprising a shell, a cable head mounted to rotate and slide in the shell, cushioning means normally resisting the relative slidable movement of said head and shell, and means associated with the cushioning means for locking said head to the shell.

7. A drilling cable socket comprising a shell, a cable head mounted to rotate and slide in the shell, cushioning means normally resisting the relative slidable movement of said head and shell, means for locking said head to the shell associated with the cushioning means, a sleeve within the shell and adapted to participate with all the movements of the cable, and resilient means associated with the sleeve, substantially as and for the purpose set forth.

In testimony whereof I have signed my name to this specification in the presence of two subscribing witnesses.

GUSTAVUS A. MONTGOMERY.
